UNITED STATES PATENT OFFICE.

HOWELL JORDAN, OF LOS ANGELES, CALIFORNIA.

SHIELD FOR CAR-HANDLES.

1,111,591.

Specification of Letters Patent. Patented Sept. 22, 1914.

Application filed December 19, 1913. Serial No. 807,741.

To all whom it may concern:

Be it known that I, HOWELL JORDAN, a citizen of the United States, residing at Los Angeles, in the county of Los Angeles 5 and State of California, have invented new and useful Improvements in Shields for Car-Handles, of which the following is a specification.

The invention relates to handle guards, 10 and more particularly to the class of shields for car handles.

The primary object of the invention is the provision of a shield wherein the handles on a car can be guarded so that passengers 15 alighting from the same can grasp the handles only when facing forward, thereby avoiding accidents resultant from alighting in the direction opposite to the direction of travel of the said car.

20 Another object of the invention is the provision of a shield of this character wherein the same can be fastened in adjusted position.

A further object of the invention is the 25 provision of a shield which is simple in construction, readily and easily adjusted, reliable and efficient in its purpose, and inexpensive in manufacture.

With these and other objects in view, the 30 invention consists in the construction, combination and arrangement of parts as will be hereinafter fully described, illustrated in the accompanying drawing, and pointed out in the claims hereunto appended.

35 In the drawing:—Figure 1 is a fragmentary side elevation of a car, showing the device constructed in accordance with the invention applied thereto. Fig. 2 is a fragmentary vertical transverse sectional view 40 through the car. Fig. 3 is a sectional view on the line 3—3 of Fig. 1. Fig. 4 is a fragmentary enlarged front elevation showing the shield shifted. Fig. 5 is a view looking toward the end of the shield.

45 Similar reference characters indicate corresponding parts throughout the several views in the drawing.

Referring to the drawing in detail, A designates a portion of the body of a closed 50 car, B the vertical posts of the door-way therein to permit the entrance to and exit from the car, as usual.

On each of the posts B is mounted a handle C, which is of the ordinary well-known construction. Adapted to be mounted upon 55 each post is the shield presently described.

The shield comprises an outwardly curved shield plate 10, formed with ends 11, to which are connected links 12, the same being pivoted at 13 thereto and also pivoted at 14 60 to the out-turned portions 15 of bearings 16 which are suitably fastened to the post B at opposite ends of the handle C thereon so that the said shield plate 10 can be swung to either side of the handle as shown. 65

Formed on the bearings 16 at the inner side of the out-turned portions 15 thereof are clamping wings 17, between which and the base of the bearings 16 is adapted to engage either edge of the shield plate 10, 70 and threaded in these wings are winged screws 18 which engage the shield plate 10 to lock the same in adjusted position. In the use of the shield the handle is rendered inaccessible at its front so that a passenger 75 turning backward when making an exit from the car cannot reach the handle which would face the passenger in the direction opposite to the direction of travel of the car, while the shield on the other handle is positioned so that a passenger will necessarily have to turn in a direction facing the travel 80 of the car for gripping said handle, thereby causing the passenger to alight from the car facing the direction of travel of the same. 85 The shield is adjustable so that the proper handle will be exposed for use according to the direction of travel of the car.

From the foregoing it is thought that the construction and manner of operation of 90 the invention will be clearly understood, and therefore a more extended explanation has been omitted.

What is claimed is:—

1. A shield for car handles comprising 95 a curved shield plate, means swingingly connecting the shield to a car whereby said shield will partly encompass the handle, and is movable relative thereto, clamps stationarily mounted for receiving either edge of 100 the shield, and means carried by the clamps for locking the shield in adjusted position.

2. A shield for car handles comprising a curved shield plate, means swingingly con-

necting the shield to a car whereby said shield will partly encompass the handle, and is movable relative thereto, clamps stationarily mounted for receiving either edge of the shield, and winged screws mounted in the clamps and engageable with the shield to lock it in adjusted position.

In testimony whereof I affix my signature in presence of two witnesses.

HOWELL JORDAN.
